UNITED STATES PATENT OFFICE.

FREDERICK D. GATCHELL, OF NEW YORK, N. Y.

DESIGN FOR AN OIL BOTTLE.

Application filed July 9, 1927. Serial No. 22,715. Term of patent 7 years.

To all whom it may concern:

Be it known that I, FREDERICK D. GATCHELL, a citizen of the United States, residing at New York, in the county of New York, and State of New York, have invented a new, original, and ornamental Design for Oil Bottles, of which the following is a specification, reference being had to the accompanying drawing, forming a part thereof.

The figure is an elevational view of an oil bottle, showing my new design.

I claim:

The ornamental design for an oil bottle, as shown.

FREDERICK D. GATCHELL.
